[57] CLAIM

The ornamental design for the camouflage skirt, as shown and described.

DESCRIPTION

FIG. 1 is a front elevational view of the camouflage skirt showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The shading in the rectangular strip shown along the top side in FIGS. 1 and 2 represents hook and loop fabric material.
